SEDGWICK N. WIGHT, OF ROCHESTER, NEW YORK, ASSIGNOR TO GENERAL RAILWAY SIGNAL COMPANY, OF ROCHESTER, NEW YORK

TRAIN-DISPATCHING SYSTEM FOR RAILROADS

Application filed March 18, 1929. Serial No. 347,910.

This invention relates to train dispatching systems of the synchronous selector type, and more particularly to the provision of means for storing a momentarily existing indication until such indication has actually been transmitted over the synchronous selector system.

In train dispatching and OS-ing systems, it is possible to transmit an OS indication over the synchronous selector system in a direct way if the OS condition exists for a period of time greater than the time required to complete one cycle of operation of the synchronous selector system. If, on the other hand, the OS condition persists for less than the time required to complete the cycle of operation of the synchronous system, it is possible for the OS condition to be lost and not transmitted to the dispatcher's office. In dispatching systems of the synchronous selector type it is the practice to indicate in the dispatcher's office the occupancy of a detector track circuit associated with a switch machine. In the case of a very short train, such as an engine and tender running along, moves over the detector track circuit, these detector track circuits usually being very short, may result in the de-energization of the detector track relay for a very short time, probably as short as 2 or 3 seconds. It is obvious that if a synchronous selector system is used in which the cycle of operation is more than this time it is possible that the OS condition is not transmitted to the dispatcher's office, but is lost, because it does not exist at the time the particular OS channel over which it must be transmitted is available for use.

In accordance with the present invention it is proposed, in view of the above mentioned and other important considerations, to employ a stick relay which is re-energized upon occupancy of the detector track circuit, and which cannot be re-energized until the synchronous selector system has passed the channel over which the condition of the detector track relay is transmitted to the dispatcher's office, from which it appears that occupancy of the detector track circuit can be transmitted to the dispatcher's office through the medium of said stick relay even though this de-

tector track circuit is occupied only momentarily.

As another object of the present invention, it is proposed to transmit a change in the position of the switch machine as well as the condition of occupancy of the detector track circuit through the medium of the same stick relay above referred to.

Other objects, purposes, and characteristic features of the present invention, will in part be apparent from the accompanying drawings and in part be pointed out hereinafter.

In the single drawing has been illustrated one embodiment of the present invention, of which drawing the left hand portion represents a dispatcher's office equipment and the right hand portion shows conventionally the way side equipment located at a distant passing siding.

In my prior application Ser. No. 120,423 filed July 3, 1926, I have shown a rather complete train dispatching system in which a polar neutral control relay Z (see Fig. 3B of said application) controls the switch machine and associated signals at one end of a passing siding. In accordance with the present invention it is proposed to control a similar polar neutral relay Z over a synchronous selector system of control, and it is proposed to transmit an OS indication to the dispatcher's office over the same synchronous selector system even through the duration of the OS condition persists for less than the time required to complete a single cycle of operation of the synchronous selector system. Since the complete circuit arrangement from the polar neutral control relay Z to the switch machine and signals has been disclosed in my prior application to which reference may be had, the disclosure of the present application will be confined to the manner of controlling the control relay Z , and the manner in which an OS indication is stored by a stick relay.

Referring to the accompanying drawings the east end of a passing siding PS of a single track railway system has been shown, including a switch machine SM for operating the track switch S, a main starting signal 2, a dwarf starting signal 2^a, a main entering signal 1, and a take-siding signal 1^a. The

switch S has associated therewith the usual detector track circuit including a track battery 3 and a track relay TD shown conventionally by a dotted line. The control relay Z 5 is controlled in accordance with the position of the two two-position direct current polar relays of the permanent magnet stick type, that is, polar relays which will remain in the last position to which they were operated by 10 permanent magnets forming part thereof. The relay WP is a switch machine repeater relay, and is energized if the switch machine assumes either extreme position. The relay OS is controlled in accordance with the conditions of the track relay TD and the switch machine repeated relay WP, in a manner as 15 will appear from the operation of the system.

In the dispatcher's office is shown a miniature passing siding PS forming part of a 20 miniature track layout conforming with the railway system to which the train dispatching system is applied, an indicating lamp I being provided to indicate the occupancy of the detector track circuit at the right hand, or 25 east end, of the passing siding. For each way-station, such as the way-station for controlling the switch machine SM and the associated signals, there is a lever suitably associated with the miniature track layout, of 30 which the lever L only has been shown. The indicating lamp I is controlled in accordance with the position of indicating relay IR, this indicating relay IR also being a two-position polar relay of the permanent magnet 35 stick type controlled over the synchronous selector system.

The relays M and N at the way-station are controlled by the lever L, and the indicating relay IR is controlled by the OS-ing relay

40 OS, through the medium of a synchronous selector system of any suitable construction conveniently shown by the rotatable contact arms RC⁰, and RC¹, which contact arms are rotated in synchronism in any suitable way.

45 *Operation.*—In order to get a more clear understanding of the present invention, as illustrated in a single embodiment, it is believed expedient to consider the operation of the particular system selected for illustration.

50 Let us assume, that the dispatcher wishes to operate the control relay Z to its right hand energized position, in order to clear a certain signal by circuits more clearly shown and described in my prior application. In order to

55 so energize the control relay Z the operator will move his lever L, and its associated contacts CM and CN, to the right hand position, and will thereby apply current of positive polarity to the relay M each time the message circuit of the synchronous selector system is closed, that is each time the rotating contacts RC⁰ and RC¹ engage the contacts 11 and 11¹ through the following circuit:—beginning at the positive side of the battery 20,

60 wire 21 and 22, contacts CM, contact 11, wire 65 contact RC⁰, line wire 24, contact RC¹, contact 11¹, wire 25, relay M, wire 26 and 27, to the common return wire C connected to the mid point of battery 20. Since, however, the relay M already assumes the right hand position, this relay M is not operated. Similarly 70 this movement of the lever L causes the application of current of negative potential to the relay N during each cycle of operation of the synchronous selector system through the 75 following circuit:—beginning at the negative side of battery 20, wires 28 and 29, lever contact CN, wire 30, contacts 12 and RC⁰, line wire 24, contacts RC¹ and 12¹, wire 31, winding of the relay N, wire 27, to common return 80 wire C connected to the mid point of battery 20. The application of current of negative polarity to the relay N operates it to the left hand position, thereby applying current of positive polarity to the control relay Z 85 through the following circuit:—beginning at the positive side of battery 35, wire 36, contact 37 of the relay M, wire 38, contact 39 of the relay N, wire 40 and 41, winding of the relay Z, wire 42, back to the mid point of battery 35. The completion of this circuit will energize the relay Z to its right hand energized position.

90 Let us now assume that the dispatcher wishes to de-energize the control relay Z, and moves his lever L back to the intermediate position. Under this condition of the lever L positive potential will be applied to both the relays M and N, thus operating the relay N to the right hand position, the relay M already assuming the right hand position, thereby breaking the circuit for the relay Z heretofore traced and not completing another circuit.

95 Let us now assume that the lever L is moved to the left hand position. Under this condition current of negative polarity is applied to the relay M, and current of positive polarity is applied to the relay N, thereby operating the relay M to the negative position, the relay N already assuming the right hand position, under which condition the following circuit for the control relay Z is completed:—beginning at the negative terminal 100 of the battery 35, wire 43, contact 44 of relay N in its right hand position, wire 45, contact 46, of relay M in its left hand position, wire 47 and 41, winding of the relay Z, wire 42 to the mid point of battery 45, thus operating 105 the control relay Z to its left hand energized position. It is thus seen that with the lever L in the right hand position the relay Z is energized to its right hand position, with the lever L in its left hand position the relay Z assumes its left hand position and with the lever L in its neutral position the relay Z is de-energized.

110 Let us now see how operation of the switch machine is indicated in the dispatcher's office. It is noted that the contact 49 of the 115

switch machine opens the circuit for the switch repeater relay WP from the time the switch machine is initiated until it has completed its operating stroke, so that the relay WP is de-energized so long as the switch machine is operating from one to the other extreme position. The normally closed energizing circuit for the relay OS may be traced as follows:— beginning at the terminal B of a suitable source of current, front contact 50 of relay DT, wire 51, front contact 52 of relay WP, wires 53 and 54, stick contact 55 of the relay OS, wires 56 and 57, winding of the relay OS, to common return wire C connected to the mid point of said battery. It should be noted that the indicating relay IR is intermittently energized with current of positive polarity during rotation of the arms RC⁰ and RC¹ of the synchronous selector system, through the following circuit:— beginning at the terminal B of a suitable battery, front contact 58 of the relay OS, wire 59, contacts 13¹ and RC¹, wire 24, contacts RC⁰ and 13, wire 60, winding of the relay IR, wire 61 to common return wire C connected to the mid point of said battery. If now the switch machine is operated from one to the other extreme position the relay WP is de-energized at the beginning of the switch machine stroke, thus breaking the stick circuit for the relay OS heretofore traced and applying current of negative polarity to the wire 53 derived from the negative terminal N of said battery. The relay OS of course assumes its de-energized position because the magnetic flux of its magnetic circuit must pass through zero in order to flow in the reverse direction. With the relay OS once de-energized and its stick contact 55 open, it will not be re-energized by the application of current of negative polarity until the synchronous selector system has completed the indicating channel over which the indicating relay IR is operated. This indicating relay IR is operated to the negative position in response to the contact 58 assuming its retracted position. At the same time when this occurs the following pick-up circuit for the relay OS is completed:— beginning at the negative terminal N of the battery heretofore mentioned, contact 52 of relay WP in its de-energized position, wires 53 and 62, contacts 13², 63, and 13², wires 64 and 57, winding of the relay OS to common return wire C connected to the mid point of said battery. With this circuit completed the relay OS is picked up, and is stuck up through a stick circuit readily traced and including the contact 52 of relay WP in its de-energized position. During the next revolution of the synchronous selector arms RC⁰ and RC¹ the indicating relay IR is again operated to its right hand position in response to the contact 58 of the relay OS assuming its raised position. It is thus seen that the indicating lamp 1 is flashed momentarily upon initiation of the switch machine on its operating stroke. This indicating lamp I is similarly illuminated momentarily when the switch machine completes its stroke and in response thereto energizes the relay WP and again reverses the polarity of current applied to the relay OS, which reverse polarity causes the relay OS to drop long enough to energize the indicating relay IR to its left hand position after which the relay OS is picked up and again operates the indicating relay IR to its right hand position. It is thus noted that the indicating lamp I in the dispatcher's office is illuminated at the beginning of the stroke and at the end of the stroke of operation of this switch machine, thus giving the dispatcher a distinctive signal, from which he may interpret the operating characteristic of the switch machine as well as the position to which it has been moved, considering therewith the position of the lever L.

In a similar way as just pointed out in connection with de-energization of the relay WP, de-energization of the track relay TD effects de-energization of the relay OS and transmits a negative impulse to the dispatcher's office to illuminate the indicating lamp I, and in the event the track relay DT has been de-energized only momentarily, as by reason of the passage of a very short train at high speed, this de-energization of the track relay TD is manifested in the tower by the illumination of the indicating lamp I even though the contact 50 of track relay DT is opened momentarily, this by provision of the stick relay OS, which if once de-energized cannot pick up until the synchronous selector system has had an opportunity to transmit an indication to the dispatcher's office.

Although the present invention has been shown applied to a synchronous selector system in which rotating contact arms are employed for synchronously completing message channels sequentially, it is desired to be understood that the invention is applicable to other systems in which the message channels are sequentially closed by other apparatus, such as sequentially-operated channel selecting relays.

Having thus shown and described one specific embodiment of the present invention, it is desired to be understood that the particular embodiment of the invention illustrated has been selected for the purpose of facilitating describing the nature thereof and its operating principles, and not with the intent of limiting the invention to the particular arrangement shown, and it is to be understood that various changes, modifications, and additions may be made to adapt the invention to the particular dispatching problem encountered in practicing the invention,

all without departing from the spirit or scope thereof, or the idea of means underlying the same, except as demanded by the scope of the following claims.

5. What I claim is:—

1. In a train dispatching system of the synchronous selector type, the combination with means for closing a large number of message circuits each including the same line wire sequentially, of an OS-ing relay which if energized supplies one of said message circuits with current of one polarity and when de-energized supplies such message circuit with current of the opposite polarity, and means effective if said OS-relay is de-energized for preventing re-energization thereof until said one message circuit has been supplied with current of said opposite polarity.
2. In a train dispatching system of the synchronous selector type, the combination with means for closing a large number of message circuits each including the same line wire sequentially, of an OS-ing relay which if energized supplies one of said message circuits with current of one polarity and when de-energized supplies such message circuit with current of the opposite polarity, a normally closed energizing circuit for said OS-ing relay including a front contact of said relay thus constituting a stick circuit, and a pick-up circuit for said OS-ing relay including contacts of said synchronous selector closed only momentarily during each cycle of operation of said synchronous selector.
3. In a train dispatching system of the synchronous selector type, the combination with means for closing a large number of message circuits each including the same line wire sequentially, of an OS-ing relay which if energized supplies one of said message circuits with current of one polarity and when de-energized supplies such message circuit with current of the opposite polarity, a normally closed energizing circuit for said OS-ing relay including a front contact of said relay thus constituting a stick circuit, and a pick-up circuit for said OS-ing relay including contacts only when said one message circuit is closed.
4. In a train dispatching system of the synchronous selector type, the combination with means for closing a large number of message circuits each including the same line wire sequentially, of an OS-ing relay which if energized supplies one of said message circuits with current of one polarity and when de-energized supplies such message circuit with current of the opposite polarity, a normally closed stick circuit for said OS-ing relay including a front contact of said OS-ing relay a front contact of a switch machine indicating relay and a front contact of a track relay, and a pick-up circuit for said OS-ing relay including contacts of said synchronous selector closed only momentarily

during each cycle of operation of said synchronous selector and front contacts of said track relay.

5. In a train dispatching system of the synchronous selector type, the combination with means for closing a large number of message circuits each including the same line wire sequentially, of an OS-ing relay which if energized supplies one of said message circuits with current of one polarity and when de-energized supplies such message circuit with current of the opposite polarity, a normally closed stick circuit for said OS-ing relay including a front contact of said OS-ing relay a front contact of a switch machine indicating relay and a front contact of a track relay, and a pick-up circuit for said OS-ing relay including contacts of said synchronous selector closed only momentarily during each cycle of operation of said synchronous selector and including front contacts of said switch machine repeater relay.

6. In a train dispatching system of the synchronous selector type, the combination with means for closing a large number of message circuits each including the same line wire sequentially, of an OS-ing relay which if energized supplies one of said message circuits with current of one polarity and when de-energized supplies such message circuit with current of the opposite polarity, a normally closed stick circuit for said OS-ing relay including a front contact of said OS-ing relay a front contact of a switch machine indicating relay and a front contact of a track relay, and a pick-up circuit for said OS-ing relay including in series contacts of said synchronous selector closed only momentarily during each cycle of operation of said synchronous selector and including front contacts of said track relay and said switch machine repeater relay.

7. In a train dispatching system, of the synchronous selector type, the combination with means for closing a large number of message circuits each including the same line wire sequentially, of an OS-ing relay which if energized supplies one of said message circuits with current of one polarity and when de-energized supplies such message circuit with current of the opposite polarity, a normally closed stick circuit for said OS-ing relay including a front stick contact of said OS-ing relay a front contact of a switch machine indicating relay and a front contact of a track relay, another stick circuit for said OS-ing relay including the said front stick contacts of said OS-ing relay and back contacts of said switch machine relay, the first stick circuit of which energizes said OS-ing relay with direct current of positive polarity and the second stick circuit of which energizes said OS-ing relay with direct current of negative polarity, a pick-up contact for shunting said front stick

contact of said OS-ing relay closed only momentarily during each cycle of operation of said synchronous selector, whereby if said switch machine indication relay is de-energized said OS-ing relay assumes its de-energized position in spite of the immediate application of current of reverse polarity and it is assured that this de-energized condition of the OS-ing relay is transmitted over the selector system even though the OS-ing relay was de-energized only for an instant.

8. In a synchronous selector train dispatching system, the combination with means for closing a large number of message circuits each including the same line wire sequentially and extending from a local dispatcher's office to a distant way station, a polar neutral control relay at said distant way station, a three-position lever at said dispatcher's office, and means for causing said polar neutral relay to assume any one of its three conditions depending on the position assumed by said three-positioned lever and including two of said message circuits.

9. In a synchronous selector train dispatching system, the combination with means for closing a large number of message circuits each including the same line wire sequentially and extending from a local dispatcher's office to a distant way station, a three-position lever at said dispatcher's office, a control relay at said distant way station, two direct current polar relays of the permanent magnet stick type located near said control relay, a circuit and a source of current for causing said control relay to assume one energized position when one of said polar relays assumes one polar position and the other polar relay assumes the reverse polar position, another circuit including said source for causing said control relay to assume the opposite energized positions when the first mentioned polar relay assumes the reverse position and the second mentioned polar relay assumes said one polar position and for causing said polar neutral relay to assume the de-energized positions when said two polar relay assume like polar positions.

10. In a centralized traffic controlling system of the synchronous selector type, the combination with a synchronous selector system including means for sequentially rendering available a large number of message circuits connecting a central office and a distant way station during each cycle of operation of said selector system, a switch machine operated through the medium of said selector system, a stick relay at said way station for controlling an indicator at said central office through the medium of said selector system, a track relay, and means effective to pick up said stick relay during each cycle of operation of said selector system except when both said switch machine assumes

an extreme position and said track relay is deenergized.

11. In a centralized traffic controlling system of the synchronous selector type, the combination with a synchronous selector system including means for sequentially rendering available a large number of message circuits connecting a central office and a distant way station during each cycle of operation of said selector system, a switch machine operated through the medium of said selector system, a stick relay at said way station for controlling an indicator at said central office through the medium of said selector system, and means effective to pick up said stick relay in each cycle of operation of said selector system if said switch machine assumes an intermediate position.

In testimony whereof I affix my signature.
